UNITED STATES PATENT OFFICE.

WALLACE F. GOODNOW, OF GREENWICH, CONNECTICUT, AND GEORGE H. VICKERS, OF EASTWOOD, NEW YORK, ASSIGNEES TO PIERCE, BUTLER & PIERCE MANUFACTURING CORP., OF SYRACUSE, NEW YORK, A CORPORATION OF NEW YORK.

UPRIGHT SECTIONAL BOILER.

Application filed December 24, 1923. Serial No. 682,424.

To all whom it may concern:

Be it known that we, WALLACE F. Goodnow and GEORGE H. VICKERS, citizens of the United States of America, of Greenwich and Eastwood, respectively, in the counties of Fairfield and Onondaga, respectively, in the States of Connecticut and New York, respectively, have invented new and useful Improvements in Upright Sectional Boilers, 10 of which the following, taken in connection with the accompanying drawings, is a full, clear, and exact description.

This invention relates to steam and hot water heaters of the upright hollow section 15 type and refers more particularly to the means for supporting and operating the grate bars and their relation to the draft and clean-out openings of the ash pit.

In heaters of this character, considerable 20 difficulty is experienced in the free operation of the grate bars owing to the accumulations of ashes, clinkers and coal upon the gears or other connections by which rotary motion is transmitted from one grate bar to 25 another.

Furthermore, it is desirable to provide 30 means for turning the grate bars by hand from the front of the heater and at the same time to extend the grid portions of the bars under the entire area of the combustion chamber and when the gears or other connections for transmitting motion from one 35 grate bar to another are mounted upon the front ends of the bars, it is necessary to reduce the grid length of the bars or to lengthen the front end of said bars for convenient manipulation by the usual hand cranks.

The main object therefore, of our present invention is not only to avoid the collection 40 of ashes, clinkers and coal upon the mechanism for transmitting motion from one bar to the other, but also to avoid the necessity for shortening the grate bars or lengthening the front ends thereof for operation by the hand crank and at the same 45 time, enabling the grid portions of the bars to extend across the entire bottom of the combustion chamber.

Another object is to provide means 50 whereby the grate bars may be conveniently and expeditiously removed for repairs or other purposes without displacing the gears from their housing and also to permit the

removal of the gears without displacing the 55 grate bars.

Other objects and uses relating to specific parts of the heater will be brought out in the following description.

In the drawings:

Figure 1 is a longitudinal vertical sectional view of a sectional steam or hot water heater embodying the various features of my invention.

Figure 2 is a transverse vertical sectional view taken in the plane of line 2—2, Figure 60 1 except that portions of one side of one of the boiler sections is broken away to show the double baffle between it and the next adjacent section.

Figure 3 is a horizontal sectional view 70 taken in the plane of line 3—3, Figure 1.

As illustrated, this heater comprises a series of hollow upright sections —1—, —2— and —3— arranged face to face in sequence from front to rear and clamped together by 75 suitable tie rods or bolts —4— which are passed through registering openings in uncored portions of the bottom and top walls of said sections at opposite sides of their vertical centers where they are protected 80 against deterioration by the heating fluid or by the products of combustion, and also permit limited expansion and contraction of the sections without overstraining the bolts.

The central and lower portions of the intermediate sections —2— are provided with similar registering openings from front to rear to form a combustion chamber —5— and an underlying ash pit —6— and also 90 to receive a plurality of grate bars —7— forming the bottom of the combustion chamber and top of the ash pit.

The front and rear sections —1— and —3— extend across and constitute the front and rear walls of the combustion chamber 95 —5— and ash pit —6— and have their inner sides chambered to conform in outline with the openings in the intermediate section to form continuations of the combustion chamber —5— and ash pit —6—.

The upper portions of the sections —1—, —2— and —3— are provided with horizontally extending registering openings to form a fire flue —8— extending horizontally from front to rear above and in spaced relation to the opening which forms the combustion

chamber —5—, said flue —8— having its rear end communicating with an outlet —9— which is adapted to be connected in any suitable manner to a chimney or other draft flue.

The portions of the upright sections between the flue —8— and combustion chamber —5— are hollow to form water containing partitions or passages —9— communicating with the hollow portions of the sections at opposite sides of said flue and combustion chamber.

The opposite sides and bottom portion of each section are also hollow to form water legs —10— and a water-containing base —11— communicating with each other and a water passage in the hollow partition —9—, and also with the upper portion or dome —12— of each section.

20 The base portions —11— and dome portions —12— of the several sections are provided with horizontally registering apertures for receiving hollow connecting nipples —13— and establishing communication between the water and steam chambers of all of the sections in sequence, the rear section being provided at its upper end with an up-flow conduit —14— registering with the adjacent nipples —13— and at its lower end with a return-flow conduit —15— registering with the corresponding nipples —13— whereby the heating fluid is allowed to circulate through the heating system and return to the heater.

35 The adjacent walls of the portions of the sections above the flue —8— constituting the domes —12— are arranged in close relation to each other so that the lower walls of said dome or upper wall of the flue —8— 40 constitute what may be termed a crown sheet of the combustion chamber and flue extending from side to side of the sections and therefore, serve to deflect the products of combustion which may enter the flue from the combustion chamber rearwardly to the outlet —9—.

The adjacent walls of the several sections below this crown sheet or upper wall of the flue —8— are provided with upright passages —16— and —17— leading from the upper portion of the combustion chamber —5— to the flue —8— while the central portions of the hollow partitions —9— are enlarged forwardly and rearwardly to substantially the width of their respective sections for dividing the passages —16— and —17— one from the other and permitting the products of combustion to pass from the combustion chamber through either or both of the passages 16 and 17 to the flue —8—.

Arranged in these passages, are suitable baffle plates —18— and —18'— forming the subject matter of our pending application, Serial Number 682,425, filed December 24, 1923, and adapted to be adjusted to

different positions for regulating the effective capacity of the passages and also for regulating the direction of flow of the products of combustion.

The front section —1— is provided with a fuel opening —20— leading to the combustion chamber —5— and normally closed by a suitable door —21—.

The front end of the flue —8— is normally closed by a door —22— adapted to be opened when desired for cleaning purposes.

The lower portion of the front section —1— is also provided with a normally closed door —23— extending across the front end of the ash pit —6— and grate bars —7— and adapted to be opened at will for removing the ashes from the ash pit and also for removing the grates when desired, it being understood that the ash pit extends from the rear section —3— through the intermediate and front sections and is therefore, of approximately the same horizontal area as that of the lower portion of the combustion chamber.

25 The door —23— is provided with suitable openings registering with the front ends of the two outer grate bars to receive a shaker handle; said openings being normally closed by supplemental doors —24—.

The lower portion of the rear section —3— is provided with a draft opening —25— normally closed by a door —26— which is adapted to be opened at will by an operating rod —27—, Figure 1, to regulate the draft, said draft opening communicating with the ash pit —6— below the grate bars —7—.

An angular guard plate —28— is removably secured by bolts —29— to suitable lugs on the inner walls of the upright water legs of the front section —1— within the clean-out opening of the ash pit —6— for receiving and supporting the front ends of the grate bars —7— and also for preventing the passage of ashes, clinkers and coal from the combustion chamber to the ash pit at the front ends of the grate bars which extend forwardly through and beyond the upright portion of the angle plate —28— and have their front ends angular in cross section for the reception of a suitable shaker handle, not shown, but by which the grate bars may be turned about their axes.

The rear ends of the grate bars are journaled in suitable openings —30— in the rear section —3— which is provided with a gear pocket or housing —31— opening from its rear face for receiving suitable gears —32— by which rotary motion may be transmitted from one grate bar to another, the rear open-side of the pocket —31— being normally closed by a removable plate —33— which is held in place by clamping screws —34—, Figure 3.

The rear ends of the bars are preferably

geared together in sets of two each whereby those of either set may be operated by the application of the shaker handle to the front end of either bar of that set as shown more clearly in Figure 3.

It is now clear that the front wall of the rear section —3— in which the rear ends of the grate bars are journaled forms the rear wall of the combustion chamber —5— and 10 protects the gears —32— from contact with the ashes, clinkers or coal in the combustion chamber and also from the water of all of the sections and brings the gears wholly within the cross sectional area of the rear 15 section thereby avoiding the necessity for elongating the front ends of the grate bars and on the whole, affording a more compact assembly of the sections of the heater.

It is also evident that by opening the door 20 —23— and removing the angle plate —28—, the grate bars may be removed forwardly without displacing the gears —32— from the pocket —31—, it being understood that the rear ends of the bars are angular in cross 25 section and are slidably inserted in similar openings in the gears to permit such withdrawal.

Under this construction, the gears —32— may be withdrawn from the rear ends of the 30 grate bars by simply removing the plate —33— and then sliding the gears rearwardly from the adjacent ends of the bars, all of which contributes to the economic assembly 35 of the grates and also to the economic withdrawal of the grates or gears for repairs and at the same time avoids any possibility of 40 clogging the gears by the accumulations of ashes or clinkers thereon.

The placing of the gears on the rear ends 45 instead of on the front ends of the grate bars within the pocket —31— where they are protected by the inner wall of the rear section —3—, leaves a free open space at the front along the lower and upper faces of the grate bars for loosening and removing clinkers and ashes and permits the use of an ash pan 50 in the ash pit when desired without in any way interfering with the gears.

The operation of our invention will now 55 be readily understood upon reference to the foregoing description and accompanying drawings, and while we have shown and described gears as the means for transmitting motion from one grate bar to the other, it is evident that other means may be employed in the pocket —31— and that the front ends of the grate bars may be otherwise supported, without departing from the spirit of this invention.

We claim:

1. An upright sectional boiler having one of its end sections provided with water legs forming portions of opposite sides of the combustion chamber and ash pit and provided with a gear chamber in its outer end face at a level between the combustion chamber and ash pit and between the water containing legs, grate bars extending thru openings in the inner wall of the gear chamber, and gears mounted on the grate bars within 60 the gear chamber. 65

2. An upright sectional boiler having one of its end sections provided with water legs forming portions of opposite sides of the combustion chamber and ash pit and provided with a gear chamber in its outer end face at a level between the combustion chamber and ash pit and between the water containing legs, grate bars extending thru openings in the inner wall of the gear chamber, 70 gears mounted on the grate bars within the gear chamber, and a cover plate secured to said end section across the outer end of the gear chamber for concealing the gears therein. 75

3. An upright sectional boiler having one of its end sections provided with water legs forming portions of opposite sides of the combustion chamber and ash pit and provided with a gear chamber in its outer end 80 face at a level between the combustion chamber and ash pit and between the water containing legs, grate bars extending thru openings in the inner wall of the gear chamber, and gears mounted on the grate bars within 85 the gear chamber, the water containing chamber in said legs extending entirely around the gear chamber. 90

4. An upright sectional boiler having one of its end sections provided with water legs forming portions of opposite sides of the combustion chamber and ash pit and provided with a gear chamber in its outer end face at a level between the combustion chamber and ash pit and between the water containing legs, grate bars extending thru openings in the inner wall of the gear chamber, and gears mounted on the grate bars within 100 the gear chamber, said gears being splined 105 on the adjacent ends of the respective grate bars for axial removal therefrom. 110

In witness whereof we have hereunto set our hands this 11th day of December, 1923.
